UNITED STATES PATENT OFFICE.

WILLIAM J. HALL, OF CINCINNATI, OHIO, ASSIGNOR OF ONE-HALF TO CHARLES MILLS,
OF CINCINNATI, OHIO.

FOLDING BOX.

1,269,706.

Specification of Letters Patent. Patented June 18, 1918.

Application filed October 20, 1915. Serial No. 56,970.

To all whom it may concern:

Be it known that I, WILLIAM J. HALL, residing at Cincinnati, Hamilton county, State of Ohio, have invented certain new and useful Improvements in Folding Boxes, of which the following is a clear, full, and exact description, attention being called to the drawing which accompanies this application and forms a part thereof.

10 This invention concerns boxes formed of blanks which consist of foldable material, like heavy paper, card-board or paste-board for instance and are cut to a certain shape which contains the sides of the box so that, 15 when such blanks are folded in a certain manner, said sides may be arranged to engage each other in proper relative position to form the boxes and to close the same.

The principal object of this invention is to 20 produce a box of this character which, after having been formed out of the blank therefor, retains its shape and the sides of which maintain their respective relative positions and also their box-closing engagement with 25 each other without the aid of additional sustaining means such as wrapping paper, twine or devices involving the use of an adhesive substance like so-called "stickers."

This feature renders this box a very desirable medium for shipping purposes in any manner as for instance through the mails and more particularly through the parcel post service thereof, inasmuch as the arrangement is such that inspection of the 35 contents is rendered possible without impairing the security of the box.

The invention concerns more particularly improvements in the box illustrated in Patent No. 1,158,047, applied for by me and 40 issued on October 26th, 1915, the object of the improvements being to produce a construction which permits the use of blanks in which the waste of material is reduced to the lowest possible minimum. Other effects 45 obtained by the improvements are increased convenience in packing and increased compactness and security of the closed box by reducing the number of edges of the blank which appear at the longitudinal corners of 50 the box.

The invention consists of the construction as hereinafter described and claimed and as illustrated in the accompanying drawing in which:

55 Figure 1. shows at reduced scale a plane-

view of a blank shaped as contemplated by my improvements, so that, when it is folded in the prescribed manner, a box results which contains the novel features of my invention.

Fig. 2. in a perspective view shows the blank while being bent and folded for the purpose of forming the box.

Fig. 3. in a similar view shows progress of the folding manipulation to the stage when the box is ready for closing.

Fig. 4. is a longitudinal section of the closed and locked box, and

Fig. 5. is a cross-section of the same.

In the drawing A indicates the bottom of the box. Letters B—B indicate the sides thereof contiguous to the bottom. The top is formed by two flaps C—D which are overlapped for the purpose, one contiguous to each one of the sides and continuous therewith. The sides are held to each other by locking flaps E—E at one end of the box and by locking flaps F—F at the other end and when said flaps are interlocked with each other as shown in Figs. 2, 3 and 5. These locking flaps form continuous parts of sides B—B, extending from their upright edges, there being such a flap at each one of these edges. When so interlocked, they hold these sides in proper relative position with reference to each other and to bottom A, to form the box.

To permit such interlocking, these locking flaps are notched as shown at e—e and at f—f respectively, and their inter-engagement is effected in the manner illustrated in Fig. 2, and while sides B—B are being bent up to position.

Before this is being done flaps G, one at each end of bottom A are bent up so that one is inside of flaps E—E and the other inside of flaps F—F, after these flaps are engaged to each other. The box so formed is now ready for use and retains its shape to permit packing which may be readily done in the most convenient manner.

While this is being done, particular attention is paid to the placing of the contents which are closely crowded against said flaps G G, so that these latter are pushed outwardly and against the locking flaps at each end whereby these flaps are closely held in their engagement remaining securely locked and maintaining the box in compact shape. After that, the box is closed for which pur-

pose flap C is first turned in as indicated in Fig. 2 so as to cover the contents of the box. Next flap D is turned over flap C as shown in Fig. 3, forming the outer top, after which 5 the closure is completed by locking this top in position.

For the purpose of such locking closing flaps H—H which terminate in locking tongues J—J are used, both being continuous at each end of the top flap D. Flaps H—H are first turned down and against the interlocked locking flaps E—E and F—F respectively, as shown in Fig. 3, so as to hold these flaps flat down against each other and against. 10 15 20 25 30 35 40 45 50 55 60 65 70 75 80 85 90 95 100

upstanding flaps G—G. Finally locking tongues J—J are pushed in upwardly one at one end of the box between the interlocked locking flaps E—E and upstanding flap G inside, which contacts with them and the other between the interlocked locking flaps F—F at the other end of the box and the upstanding flap G inside, which contacts with them and as shown in Fig. 3, at farther end of the box and in Fig. 4. After so inserted the locking tongues are held in their respective inserted positions by the frictional resistance due to close contact between the interlocked locking flaps and the upstanding flaps G—G inside and which flaps exert a clamping action upon the tongues inserted between them, which action is materially aided by the contents of the box, which are closely packed against said upstanding flaps G—G and whereby they are backed up.

Furthermore, there is nothing which would favor disengagement of these tongues because such disengagement would presume a simultaneous bending of the material at points which must continuously shift as the tongues pass out from their respective positions between the locking flaps and the upstanding flaps. However, such bending cannot occur because it is resisted by the material. Nevertheless, this locking engagement is not positive and the resistance of the material is readily overcome if positive manual action is applied as is done when access to the contents is desired.

It will now be seen that such a box may 50 be quickly formed from a blank constructed as shown and may also be securely closed and locked and thereafter remain so locked with-

out the use of twine or any other auxiliary fastening means.

Obviously and for the purposes of this invention, the blank need not necessarily be an integral one, and may be made of more than one piece of material.

Having described my invention, I claim as new:

A folding box formed of a blank which contains the various parts of the box, viz. the bottom, the side-walls continuous with opposite edges of the bottom, locking flaps, one at each end of each side-wall and continuous with them, said flaps being notched, the two flaps at each end of the box being complementary to each other and adapted to interlock so as to hold the body of the box in shape for packing, a flap at one end of the bottom and adapted to occupy an upstanding position against the inside of the interlocked locking flaps at that end, a similar flap at the other end of the bottom and adapted to occupy a similar position against the inside of the interlocked locking flaps at the other end, a top flap continuous with one of the side-walls adapted to be folded down over the contents of the box after being packed, another top flap continuous with the other side-wall and adapted to be folded down over the other top flap first folded down, a closing flap at one end of this latter top flap adapted to occupy a position against the outside of the interlocked locking flaps at one end of the box, a similar closing flap at the other end of this top flap adapted to occupy a position against the outside of the interlocked locking flaps at the other end of the box and locking tongues continuous with each of these closing flaps and adapted to occupy positions between the interlocked locking flaps at each end of the box and the upstanding flaps on the inside thereof thereby securely locking the closed box without aid of extraneous fastening means and in a manner to permit opening of the box without destruction of any of its parts.

In testimony whereof I hereunto affix my signature in the presence of two witnesses.

WILLIAM J. HALL.

Witnesses:

CHARLES MILLS,
C. SPENGEL.
